UNITED STATES PATENT OFFICE.

JOHN R. GOBLE AND JAMES E. GLASGOW, OF DECATUR, ILLINOIS.

LIQUID-FUEL BURNER.

1,049,700.

Specification of Letters Patent.

Patented Jan. 7, 1913.

Application filed November 25, 1911. Serial No. 662,494.

To all whom it may concern:

Be it known that we, JOHN R. GOBLE and JAMES E. GLASGOW, citizens of the United States, residing at Decatur, in the county of Macon and State of Illinois, have invented certain new and useful Improvements in Liquid-Fuel Burners, of which the following is a specification.

This invention relates to liquid fuel burners, and more particularly to that type of such burners which are designed to be arranged within the fire-box of an ordinary cooking range, heating stoves, and furnaces, and the burner embodying the present invention is designed as an improvement on the burner shown in the application filed May 26, 1911, Serial No. 629,678.

One aim of the invention is to provide against waste of liquid fuel and to provide novel means for vaporizing the fuel, this means embodying essentially a vaporization coil which is disposed within the pan of the burner below the mixer-tube and is heated by jets of flame issuing from the mixer-tube, whereby to vaporize the fuel prior to its admission into the burner-tube.

For a full understanding of the invention reference is to be had to the following description and accompanying drawing, in which:—

Figure 1 is a view in elevation of the burner embodying the present invention, the pan being shown in longitudinal section. Fig. 2 is a top plan view of the burner. Fig. 3 is a vertical transverse sectional view on the line 3—3 of Fig. 2.

Corresponding and like parts are referred to in the following description and indicated in all the views of the accompanying drawing by the same reference characters.

In the drawing, the burner-pan is indicated in general by the reference numeral 1, and is preferably rectangular in form and includes an imperforate bottom 2, front and rear walls 3 and 4 respectively, and end-walls 5. The burner includes a mixing tube which is indicated by the numeral 6 and is formed in its under side with slits or openings 7 from which issue jets of vaporized fuel mixed with air. This tube 6 is closed at one end and mounted through one end-wall of the pan 1 and secured in place by means of a collar 8 and bolts 9. At its other end, the tube extends through the other end-wall of the pan 1 and the series of openings 7 in the tube terminates short of this last

mentioned wall, the projecting portion of the tube at this last mentioned end being imperforate, as clearly shown in Fig. 1 of the drawing.

It will be observed by referring to Figs. 1 and 2, that the tube 6 is spaced above the bottom of the pan 1. The burner tube is indicated by the numeral 10 and is supported above the mixer-tube 6 by means of a short union 11 which serves also to establish communication between the mixer-tube 6 and the burner-tube 10. The union 11 is preferably connected with the burner and mixer-tubes at points substantially midway between their ends, and the burner tube 10 is formed with slits or openings 12 in its upper side through which a mixture of vaporized fuel and air issues.

In order that the fuel may be vaporized before being fed to the mixing tube 6, there is provided a vaporizing coil which is located within the pan below the mixer tube 6, and this coil is indicated by the numeral 13 and consists of a pipe of a suitable size coiled upon itself several times, as shown in Fig. 3 of the drawing. A vaporization chamber 14 is interposed in one of the coils of the pipe 13 and beyond this chamber the pipe extends through that end-wall of the pan through which the mixer-tube 6 extends, and carries a cut-off valve 15 which controls the supply of fuel thereto, the fuel being fed to the pipe through a tube 16 leading from a fuel tank 17, and the fuel being forced from this tank by an air pump 18. The other end of the pipe 13 is also extended through said wall of the pan, preferably at a point below the mixer-tube 6 and extends beyond the open end of the projecting portion of this tube, as clearly shown in Figs. 1 and 2 of the drawing. At its said end, the pipe 13 is extended upwardly as at 19 and communicates with a nozzle 20, but has its discharge end 21 presented at the open end of the mixer-tube 6.

The burner above described is designed to have its pan and the elements associated with the pan, disposed within the fire-box of an ordinary cooking range, and in using the burner, the valve 15 is first opened so as to allow the fuel from the tank 17 to run into the coil 13 of the vaporization chamber 14. After passing through the coil, the fuel is discharged in its liquid state from the nozzle 20 into the mixer-tube 6 and as it escapes from the openings 7 of this tube, is

ignited. The jets of flame issuing from the tube impinge upon the bottom of the pan and serve to so thoroughly heat the coil 13 and the vaporization chamber 14 as to vaporize the fuel, so that in a comparatively short time the fuel will issue in a gaseous state from the nozzle 20 and be discharged into the mixer-tube 6, the air being drawn into this mixer-tube with the fuel. The mixture of gaseous fuel and air is thoroughly heated in the mixing-tube 6 and escapes from the tube into the burner tube 10 and through the openings 12 therein, at which openings it may be ignited.

Having thus described the invention what is claimed as new is:—

1. In a liquid fuel burner, a pan, a mixer-tube supported within the pan and extending at one end through one wall of the pan and having its said end open, a burner tube supported above and in communication with the mixer-tube, the mixer-tube having discharge openings presented toward the bottom of the pan, and a fuel supply pipe coiled within the pan and having one end extending through the said wall of the pan and arranged to discharge fuel into the said mixer-tube.
2. In a liquid fuel burner, a pan, a mixer-tube supported within the pan, a burner tube supported above and in communication with the mixer-tube, the mixer-tube having discharge openings presented toward the bottom of the pan and being open at one end, and a fuel supply pipe having a portion of its length arranged within the pan beneath the mixer-tube and having its discharge end positioned to discharge fuel into the said mixer-tube.

3. In a liquid fuel burner, a pan, a mixer-tube arranged within the pan and having discharge openings presented toward the bottom of the pan, a burner tube in communication with the mixer-tube, the said mixer-tube being open at one end, a fuel supply pipe having a portion of its length arranged within the pan below the mixer-tube, a vaporization chamber interposed in the said length of the fuel-supply pipe, and a nozzle supported at the end of the supply pipe and arranged to discharge into the mixer-tube.

4. In a liquid fuel burner, a pan, a mixer-tube arranged within the pan and having one end extending through one wall of the pan and open, a burner tube supported above the mixer-tube, a union establishing communication between the burner and mixer-tubes, the mixer tube being formed with openings in its under side for the discharge of fuel, a fuel-supply pipe leading through one wall of the pan and coiled beneath the mixer-tube and between the same and the bottom of the pan, the said supply-pipe leading beyond the coil, through the said wall of the pan and to a point in advance of the open end of the mixer-tube, and a nozzle carried by the last mentioned end of the supply pipe and arranged to discharge into the said mixer-tube.

In testimony whereof we affix our signatures in presence of two witnesses.

JOHN R. GOBLE. [L. S.]
JAMES E. GLASGOW. [L. S.]
